UNITED STATES PATENT OFFICE.

LUTHER B. DEMUTH, OF NEW PHILADELPHIA, OHIO.

IRRIGATING DEVICE.

Application filed April 24, 1922. Serial No. 556,262.

To all whom it may concern:

Be it known that I, LUTHER B. DEMUTH, a citizen of the United States, residing at New Philadelphia, in the county of Tuscarawas and State of Ohio, have invented certain new and useful Improvements in Irrigating Devices; and I do declare the following to be a full, clear, and exact description of the invention, such as will enable others skilled in the art to which it appertains to make and use the same.

This invention relates to an improved irrigating device which may be termed a sprinkler and one object of the invention is to provide an irrigating or sprinkling device having a rotatably mounted supply pipe provided with outlets throughout its length for directing jets of water transversely or radially of the supply pipe and having improved means for imparting rotation of the supply pipe in one direction against the action of resilient means holding the pipe against rotation and then permitting return movement of the pipe to its original position.

Another object of the invention is to so construct the means for causing rotation of the pipe against the action of the resilient means that the pipe may be caused to rotate comparatively slowly when turning against the action of the spring and then rapidly rotate when turned in a reverse direction by means of the spring thus causing the jets of water to be thrown from the supply pipe in a very effective manner for sprinkling and irrigating.

Another object of the invention is to so construct this device that the means for causing rotation of the pipe against the action of the resilient means may consist of a bucket swung from a lever arm carried by the pipe and filled with water, the pipe being rotated as the weight of the water increases and the weight of the water when reaching a certain amount causing the bucket to tilt and empty the water thus permitting reverse rotation under action of the spring.

Another object of the invention is to so mount this bucket or water receptacle that its center of gravity may be changed when so desired and thus the amount of weight needed to tilt it controlled, or in other words the bucket caused to tilt when a predetermined amount of water has passed into the

bucket and the weight of this water rotated the supply pipe a desired amount.

This invention is illustrated in the accompanying drawings, wherein:

Figure 1 is a view showing the sprinkler in elevation and in a normal position.

Figure 2 is a sectional view taken along the line 2-2 of Fig. 1.

Figure 3 is a sectional view taken along the line 3-3 of Fig. 1.

Figure 4 is a view similar to Fig. 1 showing the bucket moved downwardly by the weight of water in the bucket.

Figure 5 is a sectional view taken along the line 5-5 of Fig. 4.

Figure 6 is a sectional view taken along the line 6-6 of Fig. 4.

Figure 7 is an enlarged view showing the bucket in side elevation.

Figure 8 is a sectional view through one side of the bucket taken along the line 8-8 of Fig. 7.

Figure 9 is a sectional view taken along the line 9-9 of Fig. 7.

This sprinkler or irrigating device as it may be called is provided with a supply pipe 1 which is rotatably carried by standards 2 and will be of any suitable length desired, it being understood that an appropriate number of standards 2 will be provided according to the length of the supply pipe 1. This supply pipe is provided at points throughout its length with outlet nozzles 3 which extend as shown in Fig. 2 so that jets of water may be thrown radially from the pipe and thus trees, grass and other vegetation permitted to be sprinkled. This pipe is rotatably carried by the standards and therefore it can be turned from the position shown in Fig. 2 in which the jets of water extend as shown to the position shown in Fig. 5 and then back again to the position shown in Fig. 2. Therefore, the jets of water will be swung in the arc of a circle but will not make a complete revolution.

In order to normally hold the pipe in the position shown in Fig. 2 and yieldably resists rotation toward the position shown in Fig. 5, there has been provided a spring 4 which has one end portion connected with an anchoring element 5 by means of a link 6 and has its upper end portion connected with a cable 7 which is attached to a semi-circular block 8 anchored to the pipe 1 and posi-

105

tioned radially thereof. It will of course be understood that if found necessary this structure for yieldably holding the pipe against rotation in one direction may be 5 duplicated.

In order to rotate the pipe 1 against the action of the spring 4, there has been provided a lever arm 9 which is connected with the pipe 1 by means of a clamp 10. When 10 this lever arm is swung downwardly, the pipe will be rotated, and the jets of water will be swung in the arc of a circle and finally caused to extend from the pipe as shown in Fig. 5 instead of as shown in Fig.

15 2. In order to swing the lever arm 9 downwardly, there has been provided a water bucket 11 which is provided with a bail or handle 12, the intermediate portion of which is offset as shown at 13. Links 14 have their 20 lower ends loosely mounted upon the handle portion 13 and have their upper ends pivotally connected with the free end portion of the lever arm 9. Therefore this bucket will normally hang in a horizontal position from 25 the free end of the lever. The arms of the bail or handle 12 have their lower ends pivotally connected with rods 15 which are slidably mounted in sockets 16 which extend from opposite sides of the bucket. One 30 socket at each side is provided with a setscrew 17 which can be tightened to engage the rod 15 and thus securely hold the rod against movement and retain the handle or bail in the desired position with respect to 35 the bucket. Lugs 18 extend from the rods 15 and by engaging the depending arms of the bail limit rearward tilting of the bucket and prevent it from moving rearwardly out of a horizontal position. This bucket has 40 its forward end portion extended so that as it fills, more water is positioned in the forward end portion of the bucket and therefore as the bucket fills, this forward end portion will gradually become overweighted and the bucket will tilt forwardly to 45 empty the water. By adjusting the handle rearwardly of the bucket, a less amount of water will be necessary in order to cause tilting of the bucket and therefore the pipe 50 will not receive rotary movement to its full extent before the bucket is emptied and the spring 4 permitted to act and return the pipe to its normal position. In order to permit greater accuracy in the balancing of 55 the bucket, there has been provided a weight 19 which is positioned beneath the bucket and slidably mounted upon the bracket 20, a set-screw 21 being provided so that the weight may be held in the desired position.

60 When this device is in use, it is set up as shown and the water can be turned on. The water flows through the pipe 1 and out through the nozzle 3 from which it will be ejected in streams or jets as shown in Fig. 65 2. The pipe 1 is provided with a branch

70 pipe 22 having a controlling valve 23 so that passage of water through this pipe 22 into the hose 24 leading therefrom can be controlled. This hose 24 is engaged by a clamp 25 adjacent the free end of the lever arm or bar 9 and is extended over the free end of the lever and carried downwardly and engaged by a clamp 26 having arms extending therefrom and connected with the 75 hanger links 14 which are carried by the lever and engage the offset portion of the bail or handle of the bucket. Water from the supply pipe 1 may therefore pass through the hose 24 and serve to fill the 80 bucket 1 thus supplying the necessary weight to swing the lever 9 downwardly and rotate the pipe 1. As the water gradually fills this bucket, this turning of the pipe will be gradual and therefore the jets of water 85 passing from the nozzle 3 will swing in such a manner that the water will be well distributed. When the bucket reaches the position shown in Fig. 5, water will continue to flow into the bucket until the weight of the water in the extended forward end portion overcomes the weight in the rear end portion. 90 This bucket will then dump and the water will flow out of it. The spring 4 can then act upon the arcuate block 8 to swing the 95 arm and bucket upwardly and return the sprinkler to its normal position. By adjusting the rods 15 longitudinally of the bucket, the center of gravity of the bucket can be changed and by means of the weight 18, a finer adjustment can be accomplished. It 100 will thus be seen that if desired, the bucket can be caused to dump sooner than when the bucket is balanced as shown and the jets of water caused to have a shorter swing before the bucket dumps and the spring 105 returns the sprinkler to its normal position.

I claim:

1. A sprinkler comprising a rotatably mounted supply pipe having water outlets spaced longitudinally thereof, resilient means connected with the pipe and yieldably holding the pipe against rotation in one direction, a lever arm extending radially from said pipe, a water receptacle, a hanger loosely connected with the free end portion of the lever arm and having pivotal connection with the receptacle, said receptacle normally hanging in a horizontal position and when filled to a predetermined extent tilting to an emptying position, and a branch pipe leading from the supply pipe and terminating above the receptacle to permit gradual filling of the receptacle to slowly move the receptacle and arm downwardly and rotate the pipe against the action of the resilient means prior to dumping of the receptacle, the resilient means quickly returning the lever and supply pipe to a normal position when the receptacle is emptied.

2. The structure of claim 1 having the receptacle provided with a pivoted handle, the hanger for suspending the receptacle from the free end of the lever having pivotal connection with the lever and handle of the receptacle. 50
3. The structure of claim 1 having the receptacle provided with a pivoted handle, the hanger for suspending the receptacle from the free end of the lever having pivotal connection with the lever and handle of the receptacle, the branch pipe being in the form of a hose and the hanger and lever being provided with clamp elements for engaging the hose and securing the same with its free end portion directed towards the open upper end of the receptacle. 55
4. The structure of claim 1 having the receptacle provided with a bail and means carried by the sides of the receptacle for pivotal connection with depending arms of the bail, said means including abutments for engaging the bail arms and limiting tilting of the bail in one direction. 60
5. The structure of claim 1 having the receptacle provided with a bail and means carried by the sides of the receptacle for pivotal connection with depending arms of the bail, said means being adjustable longitudinally of the receptacle for changing the point of support with respect to the center of gravity of the receptacle. 65
6. The structure of claim 1 having the receptacle provided with a bail, bars pivotally connected with depending arms of the bail, sockets carried by the receptacle and engaging the bars to mount the same for adjustment longitudinally of the receptacle, and means for releasably holding the bars against longitudinal movement. 70
7. The structure of claim 1 having the receptacle provided with a bail and means carried by the sides of the receptacle for pivotal connection with the depending arms of the bail, said means being adjustable longitudinally of the receptacle for changing the point of support with respect to the center of gravity of the receptacle, and a weight positioned beneath and adjustable longitudinally of the receptacle. 75
8. The structure of claim 1 having the receptacle provided with a bail and means carried by the sides of the receptacle for pivotal connection with the depending arms of the bail, said means being adjustable longitudinally of the receptacle for changing the point of support with respect to the center of gravity of the receptacle, a bracket extending longitudinally of the bottom of the receptacle, and a weight adjustable upon the bracket. 80
9. A sprinkler comprising a rotatably mounted pipe having water outlets at points throughout its length, means yieldably holding the pipe against rotation in one direction, a lever bar extending transversely from said pipe, and a receptacle suspended from said arm and adapted to be gradually filled with water to cause a slow rotation of the pipe against the action of the means yieldably holding the pipe against rotation and then dumped to permit a rapid return of the pipe to its original position. 85
10. A sprinkler comprising a rotatably mounted pipe having water outlets at points throughout its length, means yieldably holding the pipe against rotation in one direction, and means for causing the pipe to rotate slowly against the action of said means, the last mentioned means permitting the pipe to have a rapid return to its original position. 90
11. A sprinkler comprising a rotatably mounted pipe having water outlets at points throughout its length, means yieldably holding the pipe against rotation in one direction, and means for causing the pipe to rotate slowly against the action of said means, and permitting a rapid return to its original position, said means including a receptacle to be gradually filled with weight giving material and then suddenly dumped. 95

In testimony whereof I have hereunto set my hand.

LUTHER B. DEMUTH.
